UNITED STATES PATENT OFFICE.

ARCHIE E. TAUSCHE, OF LA CROSSE, WISCONSIN.

MANIFOLD HEATER.

Application filed May 18, 1922. Serial No. 561,951.

To all whom it may concern:

Be it known that I, ARCHIE E. TAUSCHE, a citizen of the United States, and a resident of La Crosse, in the county of La 5 Crosse and State of Wisconsin, have invented a new and useful Improvement in Manifold Heaters, of which the following is a full, clear, and exact description.

My invention relates to improvements in 10 manifold heaters, and it consists in the combinations, constructions, and arrangements herein described and claimed.

An object of my invention is to provide 15 a manifold heater which is portable and which may be readily secured to the intake manifold of a car.

A further object of my invention is to provide a device of the character described which has the surface disposed adjacent to 20 the manifold fashioned so as to closely engage with all portions of the manifold over which the device is disposed.

A further object of my invention is to provide a device of the character described 25 which is extremely light and may be connected with a source of current so as to quickly heat the intake manifold.

A further object of my invention is to provide a device of the character described 30 which has a novel heating element.

A further object of my invention is to provide a device of the character described which is simple in construction and which is not likely to easily get out of order.

35 A further object of my invention is to provide a device of the character described which is durable and efficient for the purpose intended, and which is relatively inexpensive to manufacture.

40 Other objects and advantages will appear in the following specification, and the novel features of the invention will be particularly pointed out in the appended claims.

My invention is illustrated in the accompanying drawings, forming part of this application, in which—

Figure 1 is a side elevation of the device shown operatively applied to an intake manifold,

50 Figure 2 is a plan view of the opposite side of the device shown in Figure 1,

Figure 3 is a longitudinal section through the device, and

55 Figure 4 is a section along the line 4—4 of Figure 3.

In carrying out my invention, I provide

two plates 1 and 2 which are preferably made of aluminum and which are of the shape shown in Figures 1 and 2. The present device is designed so as to fit the intake 60 manifold 3 of a Ford automobile, but it is obvious that the device may be manufactured in different shapes and sizes so as to be readily secured to the intake manifolds of various cars. The plates 1 and 2 are secured to each other by cap screws 4. As clearly shown in Figure 3, the plate 2 has spring clamps 5 which engage with the manifold 3 and hold the device in place (see Figures 1 and 3). In disposing the device 65 upon the manifold, the device is moved downwardly with respect to the manifold so as to cause the upper clamp 5 to engage, and is then swung clockwise with respect to Figure 1 so as to cause the lower clamp 5 70 to engage with the lower portion of the manifold 3. In this manner, the device is 75 rigidly secured in place.

The inner surface of the plate 2 is grooved at 80 6 so as to closely engage with the portion 7 of the manifold. It will be observed from Figure 2 that the groove 6 is shaped the same way as the shape of the portion 7, and the curvature of the groove is designed so as to closely contact all the wall portions of 85 the manifold covered by the heater. This construction is a decided improvement in the art of manifold heaters, since it provides a device which, when assembled, practically forms an integral part of the manifold and 90 obviates any dead air space between the heater and the manifold. In this manner the heater is adapted to function at its maximum efficiency.

The plates 1 and 2 have a heating element, indicated generally at 8, which is disposed therebetween, and which is in electrical connection with terminals 9 and 10. As clearly shown in Figure 1, the terminals 9 and 10 are connected by wires 11 with a plug 95 12 which is adapted to be inserted in any ordinary light socket. The cord 11 may be of any desired length so as to readily reach from the heater which is secured to the manifold 3 to the nearest electric light socket. The heating element 8 comprises a strip of mica 13 of the shape shown in Figure 4, a high resistance heating wire 14 and opposed mica covering sheets 22 and 23 one on each side of the wire. The wire 14 is preferably flat and is wound about the plate 13 in the manner shown in Figure 4. The ends 100 105 110

of the wire 14 are connected to the terminals 9 and 10, whereby the wire 14 is in series with the terminals 9 and 10. The wire 14 is wound about the plate 13 in such a manner 5 that the strands are parallel with respect to each other and do not engage with one another, whereby the short circuiting of the wire is obviated. The heads of the terminals 9 and 10 have metal plates 15 disposed 10 adjacent thereto, these plates receiving the ends of the wire 14 whereby a positive connection is made between the terminals and the wire.

The terminals 9 and 10 are insulated from 15 the plates 1 and 2 by means of mica bushings 16 and 17 and mica caps 18 and 19, respectively. In this manner the terminals 9 and 10 are entirely insulated from the plates 1 and 2 and are only in electrical connection 20 with the wire 14 as heretofore described. The sheet 13 is not quite as wide as the plates 1 and 2, and is bounded by a mica filler 20 (see Figure 4). This filler 20 effectually protects the heating element 8. It 25 will further be noted that the wall of the plate 2 is relatively thinner than the wall of the plate 1 and that an asbestos piece 21 is disposed between the heating element 8 and the plate 1. The heating element 8 is also 30 insulated from the plates 1 and 2 by means of mica sheets 22 and 23. From this construction it will be apparent that the heat radiated from the member 8 is directed toward the plate 2, since the plate 1 is insulated by the asbestos piece 21. In this 35 manner, practically all of the heat generated by the member 8 is conducted to the manifold 3 by means of the plate 2.

From the foregoing description of the various parts of the device, the operation 40 thereof may be readily understood. As heretofore stated, the device is readily portable, and may be easily secured to the intake manifold of the car. The groove 6 is so 45 fashioned that practically the entire outer surface of the plate 2 engages with the intake manifold 3. In this manner all of the heat generated by the element 8 is transmitted to the manifold 3. The spring clips 50 5 permit the heater to be readily secured to the manifold and to be held in adjusted position.

When applying the device to the manifold, the upper clip 5, and then the lower clip 5 55 is disposed in place and the plug 12 inserted in the electric light socket (not shown). The current may then be turned on for a few minutes so as to heat the manifold 3. Since practically all of the heat from the 60 element 8 passes into the manifold 3, current through the device may be left on only for a very short period. During this period, the heater has effectually warmed the manifold so as to warm the intake gases. It is well 65 understood that when the intake gases to

the internal combustion engine are warmed, the engine may be readily started. With the present device the heating of the gases is effectually accomplished. When the engine has been started, the device may be removed 70 from the manifold 3 by merely releasing the clips 5 from the manifold. The plate 1 forms a good conductor for heat, since it is made of aluminum and, it will be noted, that practically all of the heat from the element 8 will pass into the plate 2 and not into the plate 1, since the plate 1 is insulated by means of the asbestos lining 21. The bushings 16 and 17 and the insulating sheets 22 75 and 23 are preferably made of mica because this material is not likely to smoke when heated to a relatively high temperature. The device may be readily moved even though the current is on, since the plate 1 is cool enough to permit the ready handling of the device. As heretofore stated, the device is very simple in construction and forms an effective and efficient means for heating the intake gases of the manifold. The device is so constructed that it forms a practical integral unit with the manifold, thus obviating any dead air space between the manifold 80 and the heater.

I claim:

1. A manifold heater having a member of 95 which one side is formed to be directly in contact with the manifold substantially throughout the extent of the member, the opposite face of the member lying substantially in a plane, a heating element lying in a similar plane and applied to direct contact with the plane surface of the member, and means for securing the heater to the manifold.

2. A manifold heater having the side 105 thereof which engages with a manifold fashioned so as to closely conform to and contact the contour of the surface of the manifold covered by the heater, thereby obviating any dead air spaces between the heater and the manifold, and spring clips carried by said heater in diagonal relation to each other and being adapted to firmly hold said heater in adjusted position on the manifold, said clips permitting the heater to be readily assembled to or removed from the manifold.

3. A manifold heater comprising two longitudinal plates of a heat conducting metal secured to each other, a heating element disposed between said plates, the inner surface of one of said plates being fashioned so as to closely engage all portions of the surface of a manifold which the heater covers, and a sheet of heat non-conducting material disposed between said heating element and the other plate.

4. A manifold heater comprising a pair of heat conducting metal plates lying in opposed planes secured to each other, terminals carried by said plates and insulated there-

from, a piece of heat non-conducting material disposed between said plates, two pieces of mica disposed between one of said plates and said heat non-conductor piece, a 5 third piece of mica disposed between said first named pieces, and a wire heating element wound around said third named piece of mica, the loops of said wire being spaced from each other and the ends of said wires 10 being connected to said terminals.

5. In a manifold heater the combination of a complete member having one side adapted to contact a single side of a manifold, with a heating element in direct contact with 15 the opposite side of the member and means for securing the heater to the manifold.

6. In a manifold heater the combination of a member having one side adapted to contact a single side of a manifold throughout 20 the extent of the member, with heating means secured to the member, and means for securing the heater to the manifold.

7. In a manifold heater the combination of a member having one side adapted to contact a single side of a manifold throughout 25 the extent of the member, with heating and having another and differential surface

means secured to the differential surface of the member, and means for securing the heater to a manifold. 30

8. In a manifold heater the combination of a member having one side adapted to contact a single side of a manifold substantially throughout the extent of the member and having a differential opposite side, with 35 a heating element secured to the opposite side of the member throughout the extent of the element, and means for securing the heater to the manifold.

9. In a manifold heater the combination of a plate of a heat conducting metal having one side fashioned so as to contact all portions of the manifold covered by the heater, the opposite side of the plate having a surface out of conformity with the inner face 45 thereof, with a heating element fashioned to conform to and be in direct contact with the outer face of the plate, a sheet of heat non-conducting material disposed over the outer face of the element and covering the same, 50 and means for securing the heater to the manifold.

ARCHIE E. TAUSCHE.
